MOTOR DRIVEN SHOE BRUSH

Alvin Polatchek, New York, N.Y., assignor to Shields,
Inc., Attleboro, Mass., a corporation of Massachusetts

Filed June 4, 1962, Ser. No. 70,395

Term of patent 14 years

(Cl. D9—2)

FIG. 1 is a side elevational view of a motor driven shoe brush showing my new design;

FIG. 2 is a front elevational view thereof;

FIG. 3 is a bottom plan view thereof;

FIG. 4 is a side elevational view showing the opposite side thereof from that shown in FIG. 1;

FIG. 5 is a rear elevational view thereof;

FIG. 6 is a top plan view thereof; and

FIG. 7 is an end elevational view of a modified form thereof, the remainder of the shoe brush being the same in appearance as the form shown in FIGS. 1-4 and 6, the rotary brush member being broken away for convenience of illustration.

I claim:

The ornamental design for a motor driven shoe brush, as shown and described.
